US00D993578S

(12) **United States Design Patent** (10) **Patent No.:** **US D993,578 S**
Govil (45) **Date of Patent:** **** Aug. 1, 2023**

(54) **SMART DESK**

(71) Applicant: **Cemtrex Inc.**, Brooklyn, NY (US)

(72) Inventor: **Saagar Govil**, Brooklyn, NY (US)

(73) Assignee: **Cemtrex Inc.**, Brooklyn, NY (US)

(**) Term: **15 Years**

(21) Appl. No.: **29/762,001**

(22) Filed: **Dec. 14, 2020**

(51) **LOC (14) Cl.** **14-02**

(52) **U.S. Cl.**

USPC **D14/306**; D14/373; D6/641

(58) **Field of Classification Search**

(57) **CLAIM**

The ornamental design for the smart desk, as shown and described.

DESCRIPTION

FIG. 1 is a right side perspective view of a smart desk showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the figures depict portions of the smart desk that form no part of the claimed design. Additionally, the unshaded surface in FIG. 7 bounded on all sides by broken line features forms no part of the claimed invention.

1 Claim, 7 Drawing Sheets
